UNITED STATES PATENT OFFICE.

JUDSON C. PEWTHER, OF FORT BLISS, TEXAS.

TOY PROJECTILE.

1,261,957.

Specification of Letters Patent.

Patented Apr. 9, 1918.

Application filed July 11, 1917. Serial No. 179,942.

To all whom it may concern:

Be it known that JUDSON C. PEWTHER, a citizen of the United States, residing at Fort Bliss, in the county of El Paso and State of Texas, has invented certain new and useful Improvements in Toy Projectiles, of which the following is a specification, reference being had to the accompanying drawings.

This invention relates to toys, and particularly to arrows or like projectiles.

The general object of the invention is the provision of an arrow which may be safely shot or projected by children without danger of the arrow injuring any object or hurting the child.

A further object of the invention is to provide an arrow which may be projected for the purpose of killing flies and which is so constructed that it cannot mash the fly but will simply kill it.

Other objects will appear in the course of the following description.

My invention is illustrated in the accompanying drawings, wherein:—

25 Figure 1 is a side elevation of a toy projectile having one form of resilient head;

Fig. 2 is a like view to Fig. 1, but showing another form of head;

Fig. 3 is a like view to Fig. 1, but showing 30 still another form of head;

Fig. 4 is an elevation of the head looking at right angles to the Fig. 3;

Fig. 5 is a diagrammatic view showing the manner in which the wire gauze is folded 35 to form the head illustrated in Fig. 3.

Referring particularly to Fig. 1, 10 designates the shaft of the arrow which may be provided with wings or not, as desired, and which may be notched at its winged end 40 or not, as desired, depending upon whether the arrow is projected from a bow or from a pop-gun or like device. The opposite end of the arrow carries a substantially bulbous head 11, which in the construction illustrated in Fig. 1 is formed of a plurality of

45 fine wires, not interwoven with each other, but simply bent around to form a substantially globular head, the wires being brought around the shaft and a wrapping 12 holding

50 the wires in close engagement with the shaft. The wires 11 are slightly resilient so that the bulbous head will yield upon striking an object and the impact of the arrow will be cushioned.

In Fig. 2 I show another form of the invention, in which the shaft 10^a at one end is provided with a bulbous head 14 formed by taking a blank of wire gauze, folding or bending its edges so as to surround the end of the shaft, which is somewhat enlarged as 55 at 13 for this purpose, and then binding this last named portion of the blank to the head 13 of the shaft by means of a wrapping of wire 15.

In Fig. 3 I show the preferred form of the 60 invention, in which a relatively oblong piece 16 of wire gauze has its ends bent around and disposed on each side of the shaft 10^b, the lateral corners of the wire gauze being 65 bent inward as at 17 and the head so formed 70 being held upon the shaft by means of a wrapping of wire 18 and a covering, as for instance a covering of adhesive tape, designated 19.

This form of my invention is preferred 75 because of the relative ease with which it may be made and because of the relatively large lateral opening through the head formed by the wire gauze 16 which will permit the outward movement of the air when 80 the arrow impacts on an object so that if for instance the object be a fly, the air in front of the projectile will not force the fly out of the path of movement of the projectile. Furthermore, this form of the 85 device may be made to have a greater strength and resilience than the other forms of the device so that it will last longer and have greater cushioning power. In all forms of my device, the wire gauze, when formed into 90 the bulb, or the equivalent thereof, is resilient to a greater or less extent.

It will be seen that an arrow of this kind may be used by children without any danger of its injuring another child or injuring objects against which it is projected and, furthermore, it can be used as a means for killing insects, such as flies, water bugs, etc.

Having described my invention, what I 95 claim is:—

1. An arrow of the character described comprising a shaft and a head mounted on the end of the shaft, the head consisting of a section of wire gauze bent to arch over the end of the shaft in spaced relation 105 thereto.

2. An arrow of the character described comprising a shaft and a head formed of a

strip of wire gauze, the ends of which are bent inward to engage with the shaft of the arrow to thereby cause the main body of the wire gauze to be disposed in spaced relation to the end of the shaft, the extremities of the wire gauze strip being attached to the shaft.

3. An arrow having a shaft and a sub-

stantially bulbous hollow head of wire gauze.

In testimony whereof I hereunto affix my signature in the presence of two witnesses.

JUDSON C. PEWTHER.

Witnesses:

MRS. J. L. HEATHERLY,
VIRGINIA THOMAS PEWTHER.
